UNITED STATES PATENT OFFICE.

CLARENCE E. BEMENT, OF LANSING, MICHIGAN.

HARROW.

SPECIFICATION forming part of Letters Patent No. 399,731, dated March 19, 1889.

Application filed January 31, 1889. Serial No. 298,210. (No model.)

To all whom it may concern:

Be it known that I, CLARENCE E. BEMENT, of Lansing, in the county of Ingham, State of Michigan, have invented a new and useful 5 Improvement in Spring-Tooth Harrows, of which the following is a specification.

My invention relates to spring-tooth harrows, and its object is to provide means by which the ordinary curved tooth in a spring-10 tooth harrow can be most securely and firmly fastened to the frame-work.

Figure 1 is a vertical section across the frame-work in the plane of one of the teeth. Fig. 2 is a perspective view of this part of the 15 frame or supporting-beam with the tooth in position therein. Fig. 3 is a perspective view, on an enlarged scale, of the part of the frame-work in which the tooth is secured.

My invention is equally fitted for holding 20 curved teeth which are attached to the upper side of the frame-work and extend out to the rear and downward and teeth which are attached to the under side of the frame and extend forward, then up over the frame, and 25 then backward and down to the ground. The former arrangement is the one shown in the drawings.

B represents a portion of the frame-work crosswise, in which is cut or otherwise formed 30 the gain C, the course of which follows the direction it is desired the tooth should have. The bottom of the gain, as a whole, is slightly convex, and is grooved or corrugated transversely to its length, as shown plainly in Figs. 35 1 and 3, so as to form thereon what may be termed "knife-edge supports" or "ridges" a, which are the only points of contact between the tooth and the frame-piece B. There are two of these knife-edge supports, and this is 40 the preferred number.

A flat iron plate, A, and two bolts, c, which hold the same to the frame-piece, form a clip which completes the fastening. This clip or 45 plate A, at a point between the two ridges a, bears upon the outer face of that portion of

the tooth which lies in the gain C, which portion is thus held between the said clip and the transverse knife-edge supports or ridges a. By this means the tooth is most securely held in place without liability to slip or wobble. The bolts c pass through holes in the plate A and frame-piece B, located on opposite sides of the gain and so placed that a line extending between them will be at right angles to the general course of that portion of the tooth which is contained in the gain C. The bolts have conical heads, which fit into countersunk holes in the plate A, so as to be flush with the plate, as indicated in Fig. 2. This form of fastening is exceedingly simple, 55 and yet at the same time most effective and durable.

What I claim, and desire to secure by Letters Patent, is as follows:

1. A fastening for the curved tooth of a 65 spring-tooth harrow, consisting of a supporting frame-piece provided with a gain to receive the shank of the tooth, which gain has a transversely corrugated or grooved bottom, so as to provide transverse knife-edge supports 70 or ridges a, and a clip arranged to bear upon the outer face of the tooth at a point between the points where the inner face of the tooth meets the said supports a, substantially as described.

2. The combination of the frame-piece, formed with a tooth-receiving gain having a bottom transversely corrugated or grooved, so as to provide the knife-edge supports or ridges a, and a clip formed of the iron plate A, held 80 to the frame-piece and against the tooth by conically-headed bolts fitting in conical counter-seats in said plate, substantially as hereinbefore set forth.

In testimony whereof I have hereunto set 85 my hand this 29th day of January, A. D. 1889.

CLARENCE E. BEMENT.
